UNITED STATES PATENT OFFICE.

JOSEPH H. BOWERMAN, OF SOUTH HAVEN, MICHIGAN, ASSIGNOR OF ONE-HALF TO SAMUEL R. BOWERMAN, OF SAME PLACE.

ELASTIC-TREAD HORSESHOE.

SPECIFICATION forming part of Letters Patent No. 513,871, dated January 30, 1894.

Application filed October 11, 1893. Serial No. 487,833. (No model.)

To all whom it may concern:

Be it known that I, JOSEPH H. BOWERMAN, a citizen of the United States, and a resident of South Haven, in the county of Van Buren and State of Michigan, have invented certain new and useful Improvements in Horseshoes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective inverted view of my improved horse shoe; *i. e.*, looking at it from the under or ground side. Fig. 2 is a plan or top view of the shoe from the hoof side. Fig. 3 is an inverted perspective view of the under side of the shoe, with the rubber pad or facing removed. Fig. 4 is a cross section through the complete shoe on line $x-x$ in Fig. 2; and Fig. 5 is a cross section on line $y-y$ of Fig. 2.

Like letters of reference designate corresponding parts in all the figures.

My invention relates to horse shoes of the "racing" type; *i. e.* shoes which are principally intended for fast horses, although I desire it to be understood that my style of shoe may be used with advantage for ordinary purposes also, especially in localities where the roads are hard and not "spongy" in character.

The novelty of my improvement consists in the combination with the metal shoe proper of an elastic pad of peculiar construction, as will be hereinafter more fully described and claimed.

On the accompanying drawings, the letter A denotes the body of the shoe, or shoe proper, which is preferably of mild steel, smooth and perfectly flat on the upper side, where it is nailed upon the hoof, but having a downwardly depending rim or flange B, on the under side extending from end to end of the shoe. This flange gradually tapers from the central portion or toe, to the ends, the greatest height being at the ends, as seen more clearly in Fig. 3, and by the dotted line in Fig. 4.

The letter D designates an elastic cushion,

conforming in contour to the part A made of rubber, or some equivalent elastic and resili- 50 ent material, and is recessed or cut away along its outer edge, forming a peripheral groove E, tapering gradually from the central or toe portion to the ends, similar to but in an opposite direction to flange B; that is to say the thickest part of the cushion bearing against the flange is at the front of the shoe, where the greatest wear takes place. After the cushion has been inserted with its broad part 55 D' into the seat or recess C, back of flange B, it is fastened by means of three screws, F, viz: one at each end, where the heel-calks would be if any were used, and another at the middle, or at the arch or crown of the shoe, 60 taking the place of the toe calk. The rubber pad or cushion D is countersunk, as shown at d, to receive the beveled heads of these screws, so that they will lie flat and even with the under side of the shoe, without projection. 65

The flat part C of the metal shoe has a series of oblong nail-holes c c, as usual; the heads of the nails (not shown) being covered and protected by the broad and thick part D' of the rubber pad D. 70

To use this shoe, it is first nailed upon the hoof in the usual manner, the nails being properly clinched, after which the pad is inserted into its seat C, with its recessed or depressed edge E overlapping the raised rim or flange B, and fastened down by the flat-pointed screws F, when the shoe is ready for use. As there is no wear whatever upon the metal part of the shoe, this will last a long time, and the rubber pad or sole can be easily removed 85 and renewed whenever required, with very little trouble and at small expense.

Having thus described my invention, I claim and desire to secure by Letters Patent of the United States—

1. The combination with the metal shoe A, having a series of screw threaded apertures and nail holes, and formed with a downwardly depending flange B at its outer edge, extending from end to end of the shoe, of the elastic cushion D, formed with a peripheral groove at its upper edge, to receive the flange B, and the screws passing through apertures in the 90 95

said cushion and engaging with the screw threaded apertures in the shoe A, substantially as described.

2. The combination with the metal shoe A,
5 provided with screw threaded apertures and
nail holes, and formed with a downwardly ex-
tending flange on its outer edge, tapering
gradually from the toe or front to the ends
or heel, of the elastic cushion D, having a
10 peripheral groove tapering from the toe gradu-
ally to the heel and forming a seat for said

flange, and the screws for securing said cush-
ion to the shoe, substantially as and for the
purpose specified.

In testimony that I claim the foregoing as 15
my own I have hereunto affixed my signature
in presence of two witnesses.

JOSEPH H. BOWERMAN.

Witnesses:

WM. N. COOK,
IRVING M. SMITH.
